INTERLOCKING SYSTEM FOR RAILROADS

Edwin C. Larry and Andrew Langdon, Rochester,
N. Y., assignors to General Railway Signal
Company, Rochester, N. Y.

Application November 27, 1931, Serial No. 577,504

16 Claims. (Cl. 246—134)

This invention relates to interlocking systems for railways, and more particularly pertains to a system in which all of the interlocking between the traffic controlling devices is accomplished by 5 electrically interlocked circuits.

In one type of electric interlocking system, such as disclosed, for example, in the prior patent of S. N. Wight, Patent No. 2,027,569, dated January 14, 1936, and over which the present invention 10 is an improvement, the route circuit portions for clearing the signal of a particular route conform precisely with the various mechanical portions of the track lay-out, so that as a route is set up mechanically in the track rails, a corresponding condition is set up electrically in the 15 route circuit portions.

In accordance with the present invention, it is proposed to provide a system of the type above outlined in which the electrical route portions are 20 not completed until the locking of each of the track switches included in a route is actually completed. In other words, a lock relay, which is normally energized whenever it is safe for a track switch to be operated, but is deenergized whenever 25 a track switch should be maintained in its last operated position, is provided with back contacts that are included in those electrical route circuits which are associated with those routes that may be set up over that particular track 30 switch. This arrangement insures the reliability and safety features necessary for an interlocking system.

The present invention further provides approach locking with suitable time release means 35 associated therewith.

The present invention also provides rear release route locking, that is, a particular route may be set up with its governing signal cleared, but this route cannot be changed once a train has 40 passed beyond the governing signal. However, as the train passes beyond each track switch included within that route, that track switch is released so as to be operated in readiness for other routes in which it may be included. Associated 45 with this rear release route locking is suitable releasing means which eliminates the time element usually required for operation of the track switch after a signal has been cleared. In other words, the passage of a train in acceptance of a clear 50 signal, causes the time releasing and approach locking means for that signal to be thereafter ineffective until the signal lever has been manually restored to its normal at stop position.

Other objects, purposes and characteristic features of the present invention will be in part obvi- 55

ous from the accompanying drawings, and in part pointed out as the description of the invention progresses.

In describing the invention in detail, reference will be made to the accompanying drawings, in which like reference characters designate corresponding parts throughout the several views, and in which:—

Figs. 1A and 1B, when placed side by side, constitute an interlocking system arranged in accordance with the present invention, as applied to a simple track layout.

For the purpose of simplifying the illustration and facilitating in the explanation thereof, the various parts and circuits constituting the embodiment of the invention have been shown diagrammatically and certain conventional illustrations have been employed, the drawings having been made more with the purpose of making it easy to understand the principles and mode of operation, than with the idea of illustrating the specific construction and arrangement of parts that would be employed in practice.

The various relays and their contacts are illustrated in a conventional manner and symbols are employed to indicate connections to the terminals of batteries, or other suitable sources of electrical current, instead of showing all of the wiring connections to these terminals.

The symbols (+) and (—) are employed to indicate the positive and negative terminals respectively of suitable batteries, or other sources of electrical energy; and those circuits with which these symbols are used, are presumed to have current flowing from the positive terminal designated by (+) to the negative terminal designated by (—). If alternating current is employed, then these symbols, used to indicate the terminals of suitable sources, will represent instantaneous relative polarities.

In the accompanying drawings, the invention has been shown applied to a simple track layout including a stretch of track having two track switches connecting diverging routes thereto; but it should be understood that the invention is not limited, as thus shown, to the control of the switches and signals of such a simple layout, but may be extended for any desired number of switches and signals and may be readily applied to all types of track layouts commonly found in interlocking plants.

Apparatus

The track layout includes a stretch of track which for convenience in describing the present

invention, is divided into five track sections, namely, track sections 3, 5, 7, 9 and 11. The track section 5 is shown as including a suitable railroad track switch 5TS which serves to connect a turn-out track to the main track; and similarly the track section 9 includes a suitable railroad track switch 9TS which serves to connect another turn-out track to the main track.

The switches 5TS and 9TS are preferably operated by suitable switch machines 5SM and 9SM respectively to normal and reverse positions. These switch machines may be of any suitable type, such for example as disclosed in the patent to W. K. Howe, Patent No. 1,466,903, dated September 4, 1923, and are remotely controlled by an operator, located in a tower, through suitable control circuits represented for the purposes of the present disclosure by a dotted line extending from the respective switch machine to its control lever in the tower. More specifically, the switch machine 5SM is indicated as controlled by the switch machine lever 5SML; and similarly the switch machine 9SM is indicated as controlled by the switch machine lever 9SML, but both of these levers are preferably located in the same tower. The control circuits for these switch machine control levers with their associated switch machines, may be of any suitable type such as disclosed for example in the above mentioned patent of S. N. Wight, Patent No. 2,027,569, dated January 14, 1936. A control circuit of the type disclosed in this Wight patent, which is more particularly desirable for the system of the present invention, is of the type wherein the switch machine responds to each operation of the switch machine control lever when the lock relay for that switch machine is energized, but whenever the lock relay is deenergized the switch machine will not respond to its control lever, nor will it respond to a new position of its control lever if the lock relay becomes energized subsequent to the actuation of the switch machine control lever to such a new position. In other words, the switch machine control lever must be in correspondence with its switch machine, and the switch machine must be unlocked at the time of the operation of the control lever in order for the switch machine to respond. Also, any operation of the switch machine initiated prior to the deenergization of the lock relay is completed although the lock relay may under certain circumstances become deenergized while the switch machine is still in mid-stroke.

Although various signal arrangements might be provided for the track layout chosen for the embodiment of the present invention, only a signal 1 governing traffic in an east bound direction over the main track, signals 2—2A—2B and a signal 4 governing traffic in a west bound direction over the main track and the two turn-out tracks, have been shown. These signals are indicated as being of the light signal type, but may be of any other type, or any other suitable signalling means, governed in accordance with the present invention by signal levers located in the tower.

In actual practice some of the signalling relays, devices and the like, may be located along the trackway while other devices are located in the operator's tower, but for convenience in describing the present invention, it is assumed that the control levers for the switches and signals and their various associated controlling circuits and relays are located in the tower, and that suitable control circuits are provided for re-

mote connecting the tower with the traffic controlling devices. It is to be understood of course that any suitable distribution of the apparatus may be made without affecting the system of the present invention in its operation and usefulness. 5

The control levers are preferably mounted upon a suitable control panel with indicating lamps, miniature track switches located on a track diagram and such other sundry devices which may be associated with such a control panel to facilitate in the handling of traffic. A control lever 1SGL is provided for governing the signal 1; while a signal control lever 2SGL is provided for governing the signals 2, 2A and 2B.

The condition of occupancy of the various track sections is repeated in the tower by suitable track relays or track repeating relays indicated by the letter reference character T and associated with their respective track sections as designated by the preceding numeral. The track sections into which the track is divided by suitable insulated joints are assumed to have track circuits of the closed circuit type so that the track relays in the tower are normally picked up or energized.

The position of the track switches is indicated in the tower by switch repeating relays indicated by the letter reference characters WP and associated with the particular track switch as indicated by the preceding numerals. Each of these switch repeating relays WP is of the polar-neutral type and is energized with current of a particular polarity depending upon the particular position of its corresponding track switch and its locked condition, and whenever a track switch is unlocked, the corresponding repeating relay is deenergized. For convenience, it is assumed that the track switches 5TS and 9TS are in their normal positions and are locked, so as to energize their respective relays 5WP and 9WP with suitable potentials to actuate their polar contacts to right hand positions and to actuate their neutral contacts to energized positions.

Each switch repeating relay WP is provided with two neutral repeating relays, one relay NP energized when its relay WP indicates a normal locked position and another relay RP energized when its relay WP indicates a reverse locked position. More specifically, relays 5NP and 5RP are associated with relay 5WP, and similarly relays 9NP and 9RP are associated with relay 9WP. These relays are employed for simplifying the circuit selection through contacts which indicate the position and locked condition of the associated track switches, but it is to be understood that these relays are not essential in practicing the invention.

Lever repeating relays 1P and 2P are associated with their respective signal control levers, as indicated by their preceding numerals. Likewise, route relays 1RR and 2RR are associated with their respective signal levers for indicating whether a particular route is electrically set up.

Relays 1HR, 2HR, 2AHR and 2BHR are associated with their respective signals, as designated by the numerals preceding their reference characters. Each of these relays, when deenergized, causes its associated signal to indicate stop, but, when energized, causes its associated signal to indicate proceed subject to traffic conditions as may be required in accordance with the usual practices.

Time element relays 1TE and 2TE, preferably of the thermal type having front and back contacts, are employed with their signals for fur- 75

nishing time releasing means for the approach locking associated with such signals. These time element relays 1TE and 2TE have time element stick relays 1TES and 2TES respectively for registering their energized positions.

A track stick repeater 5TPS is provided for the track section 5 in advance of the signal 1 for the purpose of making that signal a semi-automatic stick signal, and also for the purpose of releasing the approach locking under certain conditions as hereinafter pointed out. It is of course optional whether this feature is provided for all of the signals or not, and in the specific embodiment of the present invention, this feature has been shown in connection with only one signal but may be applied to the other signals if desired.

Associated with each track section between opposing signals are two directional stick relays, one for east bound traffic and the other for west bound traffic. More specifically, relays 5ES, 7ES and 9ES are associated with track sections 5, 7 and 9 respectively for east bound traffic; and relays 5WS, 7WS and 9WS are associated with track sections 5, 7 and 9 respectively for west bound traffic. These relays provide the route locking between opposing signals and when the first directional stick relay of a route for a particular direction is deenergized as the result of the clearing of the starting signal for that route, each of the directional stick relays included within the route for that direction is caused to be deenergized, and is reenergized successively as the train passes through the route to provide the rear releasing for the track switches in the route. The directional stick relays for the opposite direction are not deenergized.

A lock relay is provided for each track switch and is controlled in accordance with the directional stick route locking relays and the track section in which the switch is located. These locking relays, namely, relays 5LR and 9LR are associated with the signal route selecting circuits and also with the switch machine control circuits, in such a manner as to prevent the operation of the corresponding switch machines in response to movement of their respective control levers whenever these locking relays are deenergized, and in a manner to prevent the clearing of a signal for a route until the lock relays for all of the switches in that route are deenergized.

It is believed that the characteristic features and purposes of the present invention will be best understood by giving the remaining description from the standpoint of typical operations.

55 Operation

Normal conditions.—Although the track switches are usually left in their last operated positions, they have been shown as being in their normal positions in correspondence with their respective switch machine control levers. The signal control levers, however, are usually returned to normal "at stop" positions, as shown, so that the corresponding signals are displaying stop indications.

With the track sections unoccupied, the track relays are normally energized with their contacts picked up. With the track relay 5T energized, the track repeating stick relay 5TPS is energized by a circuit from (+), through back contact 15 of relay 1P, windings of relay 5TPS, front contact 16 of track relay 5T, to (-). As the contacts of the relay 5TPS are picked up, a stick circuit is closed from (+), through front contact 17 of track repeating stick relay 5TPS,

windings of relay 5TPS, front contact 16 of relay 5T, to (-).

The switch repeating relays are energized in accordance with the normal positions of their respective track switches, as above mentioned, thus energizing their normal repeating relays NP by circuits obvious from the drawings.

As the signal control levers 1SGL and 2SGL are in their stop positions, the time element stick relays and the directional stick route relays for both directions are picked up, thereby closing their auxiliary stick circuits, as presently to be pointed out.

A pick-up circuit for relay 1TES is closed from (+), through back contact 18 of relay 1HR, front contact 19 of relay 3T, windings of relay 1TES, to (-). The stick circuit for this relay 1TES is thus closed from (+), through back contact 18 of relay 1HR, heating element 20 of thermal relay 1TE, front contact 21 of relay 1TES, windings of relay 1TES, to (-).

The pick-up circuit for the relay 5ES is closed from (+), through back contact 18 of signal control relay 1HR, back contact 22 of time element relay 1TE, front contact 23 of relay 1TES, back contact 24 of relay 1P, front contact 25 of track relay 5T, windings of relay 5ES, to (-). The stick circuit for this relay 5ES is closed from (+), through back contact 18 of relay 1HR, back contact 22 of relay 1TE, front contact 23 of relay 1TES, back contact 24 of relay 1P, front contact 26 of relay 5ES, windings of relay 5ES, to (-).

The pick-up circuit for the relay 7ES is closed from (+), through front contact 27 of relay 5ES, front contact 28 of track relay 7T, wire 29, windings of relay 7ES, to (-). The stick circuit for this relay 7ES is closed from (+), through front contact 27 of relay 5ES, wire 30, front contact 31 of relay 7ES, windings of relay 7ES, to (-).

In a similar manner, the relay 9ES has a pick-up circuit closed from (+), through front contact 32 of relay 7ES, front contact 33 of track relay 9T, windings of relay 9ES, to (-). A stick circuit is closed from (+), through front contact 32 of relay 7ES, front contact 34 of relay 9ES, windings of relay 9ES, to (-).

A pick-up circuit for relay 2TES is closed from (+), through back contacts 35, 36 and 37 of relays 2AHR, 2BHR and 2HR respectively, front contact 38 of relay 21T, windings of relay 2TES, to (-). The stick circuit for this relay is closed from (+), through back contacts 35, 36 and 37 of relays 2AHR, 2BHR and 2HR respectively, heating element 39 of thermal relay 2TE, front contact 40 of relay 2TES, windings of relay 2TES, to (-).

A pick-up circuit for relay 9WS is closed from (+), through back contacts 35, 36 and 37 of relays 2AHR, 2BHR and 2HR respectively, back contact 41 of relay 2TE, front contact 42 of relay 2TES, back contact 43 of relay 2P, front contact 44 of relay 9T, windings of relay 9WS, to (-). The stick circuit for this relay 9WS is closed from (+), through back contacts 35, 36 and 37 of relays 2AHR, 2BHR and 2HR respectively, back contact 41 of relay 2TE, front contact 42 of relay 2TES, back contact 43 of relay 2P, front contact 45 of relay 9WS, windings of relay 9WS, to (-).

A pick-up circuit for relay 7WS is closed from (+), through front contact 46 of relay 9WS, wire 47, front contact 48 of relay 7T, windings of relay 7WS, to (-). The stick circuit for this relay 7WS is closed from (+), through front con-

tact 46 of relay 9WS, wire 47, front contact 49 of relay 7WS, windings of relay 7WS, to (-).

A pick-up circuit for relay 5WS is closed from (+), through front contact 50 of relay 7WS, front contact 51 of relay 5T, windings of relay 5WS, to (-). The stick circuit for this relay 5WS is closed from (+), through front contact 53 of relay 7WS, front contact 52 of relay 5WS, windings of relay 5WS, to (-).

10 In other words, the directional stick relay at the beginning of a route is governed in accordance with the clearing of the starting signal for that route and the approach and time release locking associated therewith, while the remaining 15 directional stick relays are governed by their preceding directional stick relay.

The lock relay 5LR is energized through a circuit from (+), through front contact 53 of relay 5ES, front contact 54 of track relay 5T, 20 windings of relay 5LR, front contact 55 of relay 5WS, to (-).

25 The lock relay 9LR is energized through a circuit from (+), through front contact 56 of relay 9ES, windings of relay 9LR, front contact 57 of track relay 9T, front contact 58 of relay 9WS, to (-).

Establishing a route.—With the system in the normal conditions above outlined, the operator may govern the track switches to such new positions as he may desire. For example, the operator may move the switch machine control lever 5SML to its reverse dotted line position which will operate the track switch 5TS to its reverse position. The diverging route, thus established, 30 is illustrated as having a signal 2A for governing west bound train movements, but a signal governing east bound traffic has been omitted for convenience.

40 Likewise, a diverging route may be set up by moving the switch machine lever 9SML to its reverse dotted line position operating the track switch 9TS to its reverse position. This diverging route is illustrated as having a signal 2B governing west bound train movements, but the signal governing east bound train movements 45 has been omitted for the sake of simplicity.

The track switches are responsive to their respective control levers only when their respective lock relays LR are energized. For example, if the lock relay 5LR is deenergized, front contact 50 is open, thus preventing the operation of the track switch 5TS in response to the switch machine lever 5SML. Similarly, if the lock relay 9LR is deenergized, front contact 61 is open, 55 thus preventing the operation of the track switch 9TS in response to the switch machine lever 9SML. The energization and deenergization of the lock relays is dependent upon conditions explicitly explained hereinafter.

60 Although the various diverging routes may have apparatus including signals, signal levers, selecting circuits and the like, similar to those illustrated, it is considered sufficient for understanding the present invention to consider only 65 the establishment of a route over the main track involving the signals 1 and 2.

Let us assume for example then that the operator desires to set up a route for the passage of a train in an east bound direction over the main track. To do this, he positions the switch machine levers 5SML and 9SML in their normal positions after which he moves the signal control lever 1SGL to its proceed or clear position.

70 With the lever 1SGL in its proceed position, 75 the relay 1P is energized by a pick-up circuit

from (+), through lever 1SGL in a proceed position, windings of relay 1P, back contact 62 of relay 1RR, to (-).

As soon as the contacts of the relay 1P have picked up, a stick circuit is closed from (+), 5 through lever 1SGL in a proceed position, windings of relay 1P, front contact 63 of relay 1P, to (-).

The energization of the relay 1P opens both the pick-up and stick circuits of the directional 10 stick relay 5ES at open back contact 24. The deenergization of the relay 5ES opens both the pick-up and stick circuits for the relay 7ES at open front contact 27, which in turn opens both the pick-up and stick circuits of the relay 9ES 15 at open front contact 32.

The deenergization of the relay 5ES opens the energizing circuit for the lock relay 5LR allowing its contacts to drop away; and, similarly, the deenergization of the relay 9ES opens the energizing 20 circuit for the lock relay 9LR causing its contacts to drop away.

With the relays 5LR and 9LR deenergized, the respective track switches 5TS and 9TS are prevented from being governed by their respective 25 control levers 5SML and 9SML.

The deenergization of the lock relays of each of the track switches included in the route governed by the signal 1 completes its route selecting circuit from (+), through front contact 64 of 30 relay 1P, windings of relay 1RR, front contact 65 of relay 5NP, back contact 67 of relay 5LR, wire 68, front contact 69 of relay 9NP, back contact 70 of relay 9LR, windings of relay 2RR, back contact 71 of relay 2P, to (-). The current 35 which flows in this route selecting circuit energizes the relays 1RR and 2RR in series.

The picking up of the contact 81 of the relay 2RR opens the pick-up circuit of the relay 2P, so that a route in the opposite direction cannot possibly be completed by movement of the lever 2SGL to a proceed position. Should, by some coincidence, the lever 2SGL be moved to a proceed position and the relay 2P be picked up, then the potential (+), would be applied to both ends 40 of the route selecting circuit by contacts 64 and 71, so that the relays 1RR and 2RR would not be energized, thereby preventing the clearing of either the signal 1 or the signal 3. Thus, a double 45 check is provided against the setting up of opposing routes.

With the relays 1P and 1RR energized, an energizing circuit is completed for the relay 1HR from (+), through front contact 72 of relay 5TPS, front contact 73 of relay 5T, front contact 74 of relay 1RR, front contact 75 of relay 1P, windings of relay 1HR, front contact 76 of relay 1P, to (-). The energization of the relay 1HR opens the energizing circuit for the red or stop indicator of signal 1 at back contact 77 of 60 relay 1HR, and closes the energizing circuit for the green or proceed indicator of signal 1. The picking up of contact 18 of relay 1HR opens the 65 pick-up and stick circuits of the relay 1TES, for reasons which will be pointed out hereinafter.

It is to be noted, that a shunt circuit for relay 1HR is closed through wire 78 and back contact 76 when the relay 1P is deenergized. This is to protect the relay 1HR from crosses that might cause a false clear.

A route has thus been set up both mechanically 70 over the track rails and electrically through the signal route selecting circuit, in such a manner that the track switches within the route are positively locked before the signal can be cleared. 75

The system is preferably provided with suitable approach locking and time release means for the approach locking, if there are no trains upon the approach section, the signal 1, for example, may be put to stop at any time the operator may desire and the track switches included within the route may be immediately operated thereafter, as soon as the route circuits and relays have returned to their normal condition.

10 For example, when the operator returns the signal lever 1SGL to a stop position, the relay 1P is deenergized opening the energizing circuit for the relay 1HR at front contacts 15 and 16. The deenergization of the relay 1HR puts the signal 1 to stop and closes the pick-up circuit for the relay 1TES from (+), through back contact 18 of relay 1HR, front contact 19 of relay 3T, windings of relay 1TES, to (-). The energization of the relay 1TES and the deenergization 15 of the relays 1HR and 1P closes the pick-up circuit for the relay 5ES (previously traced), which in turn closes the pick-up circuit for the relay 1ES at front contact 27, in turn closing the pick-up circuit for the relay 9ES at front contact 32. 20

25 The energization of the relay 5ES closes the energizing circuit for the relay 5LR at front contact 53 permitting the operation of the track switch 5TS by the lever 5SML. Similarly, the energization of the relay 9ES closes the energizing circuit for the lock relay 9LR at front contact 56, the energization of which allows the operation 30 of the switch 9TS in response to the lever 9SML.

Approach locking.—Let us assume that the route is still set up over the main track for a train movement in an east bound direction, and that a train has passed upon the track section 3 deenergizing the track relay 3T. The signal 1 of course displays a proceed or clear indication, so that the engineer governs his train in accordance therewith throughout the track section 3, and should the operator, for one reason or another, cause the signal 1 to display a stop indication by returning the signal lever 1SGL to a stop position, the train in the track section 3 must either be provided with sufficient time to stop in advance of the signal 1, or be provided with sufficient time to enter the track section 5, where the detector locking is made effective. This predetermined time, provided for the purpose of safety, is measured off by the thermal relay 1TE for the signal 1. Similarly, the thermal time element relay 2TE is provided for measuring off the predetermined time for the signals 2, 2A and 2B.

55 More specifically, if the operator moves the signal lever 1SGL deenergizing the relay 1P and subsequently deenergizing the relay 1HR, the relay 1TES will not pick up as the front contact 19 of track relay 3T is open, but the heating element of the thermal relay 1TE is energized through a circuit from (+), through back contact 18 of relay 1HR, heating element 20 of relay 1TE, back contact 21 of relay 1TES, to (-). After a predetermined time has elapsed, the front contact 22 of the thermal relay 1TE closes a pick-up circuit for the relay 1TES from (+), through back contact 18 of relay 1HR, front contact 22 of relay 1TE, windings of relay 1TES, to (-). The opening of back contact 21 of relay 1TES 60 opens the low resistance energizing circuit for the heating element 20 and closes front contact 21 for completing the high resistance stick circuit for the relay 1TES. This stick circuit for the relay 1TES does not allow sufficient current to flow to maintain the contact 22 of relay 1TE in

its actuated position, but allows the heating element 20 to cool so that contact 22 assumes a closed back contacting position. Thus, after a predetermined time after the closing of the front contact 23, the back contact 22 is closed completing the pick-up circuit for the relay 5ES, as previously traced. The energization of the relay 5ES closes front contact 21 picking up the relay 1ES which in turn closes front contact 32 and picks up the relay 9ES. The energization of the 10 directional stick relays ES energizes the lock relays LR, as previously pointed out, allowing operation of the track switches 5TS and 9TS.

15 However, it is seen from the above description that such operation of the track switch is prevented for a predetermined time including both the heating and the cooling times of the thermal relay 1TE. This provides that the thermal relay 1TE is returned to its normal position, so that irrespective of the number of successive operations required of this relay, the total time required for a complete cycle of operation is substantially the same.

20 *Detector locking.*—Assume for convenience that the signal 1 is clear, and that the train on the track section 3 passes the signal 1 and proceeds onto the track section 5. This deenergizes the track relay 5T which opens the energizing circuit for the relay 1HR at open front contact 13 causing the signal 1 to indicate stop. The 25 deenergization of the track relay 5T also opens front contact 54 positively insuring that the lock relay 5LR can not be energized, so long as the train is on the track section 5, which provides the desired detector locking. The occupied condition of the track section 5 does not deenergize the west directional stick relay 5WS at open front contact 51 by reason of its stick circuit including front contact 52, as will be obvious from the drawings.

30 *Sectional releasing.*—The deenergization of the track relay 5T, also opens the stick circuit of the track repeating stick relay 5TPS at open front contact 16, which further opens the circuit for the relay 1HR at front contact 72. With the 35 relay 5TPS deenergized and the relay 1HR deenergized, the relay 1TES is immediately picked up through a circuit from (+), through back contact 18 of relay 1HR, back contact 80 of relay 5TPS, windings of relay 1TES, to (-). As soon 40 as the relay 1TES is picked up, its stick circuit is closed as previously pointed out. In other words, the relay 1TES is picked up by the passage of a train without requiring a time interval to be interposed after the signal 1 is automatically 45 put to stop by the passage of the train.

50 Although the relay 1HR is deenergized and the relay 1TES is energized with the back contact of relay 1TE closed, the relay 5ES is not picked up until the operator moves the signal lever 1SGL 55 to a stop position deenergizing the relay 1P and thereby closing back contact 24.

55 Even if the operator moves the lever 1SGL to a stop position as soon as the train accepts the signal 1, thereby closing back contact 24 of relay 1P, the relay 5ES can not be picked up by reason of open front contact 25, until after the passage of the train beyond the track section 5 allowing the energization of the track relay 5T.

60 When the train moves into the track section 1 and the relay 5T is picked up, then the relay 5ES is energized through its pick-up circuit, (previously pointed out) which allows the lock relay 5LR to be energized. The apparatus is then conditioned so that the operator is permitted to oper- 65 70 75

ate the track switch 5TS although the train has not passed entirely through the route originally set up.

It is noted, that the release of the section in the route as the train passes beyond each particular track section is dependent upon the restoring of the governing signal control lever to its stop position. Thus, should the train pass beyond the route before this is done, the signal 1 is maintained at stop because the relay 5TPS cannot be picked up until the relay 1P is deenergized and back contact 15 is closed by reason of the return to the normal stop position of the lever 1SGL.

15 Although the relay 5ES is picked up with the train in the track section 7, the relay 7ES does not pick up until a train has entirely passed out of the section 7 into the section 9 closing front contact 28 included in the pick-up circuit of the 20 relay 7ES. In a similar manner the relay 9ES is controlled through relay 7ES and is maintained deenergized until the train has passed into the section 11. As soon as the train is beyond the track section 9 with the relay 9ES picked up, 25 the lock relay 9LR is energized permitting the operation of the track switch 9TS.

It is noted, that the directional stick relays 5WS, 7WS and 9WS are not deenergized upon the passage of the train through the route set 30 up by the clearing of signal 1. The reason for this is quite obvious, in that it is necessary for the directional stick relays to be deenergized in an order depending upon the direction in which the route is set up, and if the first directional stick relay for a given direction is not deenergized, then the remaining directional stick relays for that direction will remain energized. This is because each directional stick relay has 35 a stick circuit which shunts the associated track 40 relay contact.

The necessity for the picking up of the relay 1TES through back contact 80 of the relay 5TPS is due to the fact that in interlocking plants trains are required to move as closely together 45 as possible to facilitate traffic. Thus, although a train is passing over the track switch 5TS, another train may be following closely on a caution signal, that is, with the home signal 1 at stop the distant signal will be caution, so that 50 the track section 3 is occupied when the operator desires to move the track switch 5TS immediately after the passage of the first train. For example, one traffic movement might be an east bound train passing over the track switch 5TS in its normal position followed by another train held on the track section 3 by the signal 1 at stop, until another east bound train has passed over 55 the track switch 5TS in its reverse position. In this case, it would be undesirable to have a time element retarding the movement of the track switch 5TS after the passage of the first train, as the train approaching the signal 1 on track section 3 is moving on a caution signal and is prepared to stop with the signal 1 at stop. Hence, 60 the shunting of the approach locking by contact 80 is a distinct advantage. It is to be understood, that, although the relay 5TPS has a back contact 80 for shunting the front contact 19 of relay 3T, a back contact on the track relay 5T may be 65 just as well employed, the relay 5TPS being used more particularly for the purpose of making signal 1 a semi-automatic stick signal.

Other features.—The route circuit portions for the route relays, as for example relays 1RR and 2RR, conform exactly to the track layout, as

more completely disclosed in the pending application of S. N. Wight, Ser. No. 540,596, filed May 28, 1931. Thus, when the track switch 5TS is reversed, the route relay 2RR has a circuit selection including front contact 85 of switch repeating relay 5RP and the circuit from the front point of this contact extends through such selections as may be required for this turn-out route and ends in the control means for the opposing signal, all of which has been omitted for the sake of simplicity, the circuit in this case being illustrated as terminating in the reference character X¹.

Similarly, when the track switch 9TS is reversed, the route relay 2RR has a circuit selection including front contact 86 of switch repeating relay 9RP, and the circuit which extends from front point of this contact extends through such selections as may be required for this turn-out route, but is shown as terminating in the reference character X².

Irrespective of the particular route which is established with the signal lever 2SGL in a clear or proceed position, the relays 2P and 2RR are both energized and the particular signal cleared is dependent upon the selections for the respective signal control relays 2HR, 2AHR and 2BHR. With a route set up for main line traffic, that is, with the switches 5TS and 9TS in normal positions, the signal control relay 2HR is energized, 30 providing the directional stick relays have been properly dropped and the lock relays are in proper position. This circuit is completed from (+), through front contact 87 of relay 5T, front contact 88 of relay 5NP, front contact 89 of relay 3T, wire 90, front contact 91 of relay 9NP, front contact 92 of relay 9T, front contact 93 of relay 2RR, front contact 94 of relay 2P, windings of relay 2HR, front contact 95 of relay 2E, to (—).

The relays 2AHR and 2BHR are selected in 40 a similar manner, but as these signal control relays govern diverging route signals, their circuits are carried through contacts as found necessary in connection with the diverging route. For convenience the circuits of these relays 2AHR 45 and 2BHR have been illustrated as ending in the reference characters X³ and X⁴ respectively. In brief, the signal control lever 2SGL accomplishes the clearing of one of the signals 2, 2A or 2B dependent upon the route set up by the positioning of the switch machine control levers. 50

It is noted, that the selections for the relay 1HR have not been carried through switch position repeating contacts; while the selections for the signal control relays 2HR, 2AHR and 2BHR have been carried through various switch repeating contacts in accordance with the routes which they govern. This selection of circuits for the signal control relays is necessary only when the signals, which they control, govern routes which have facing point switches. It is also noted, that extended track circuit control for the signal control relays 2HR, 2AHR and 2BHR is provided, but there are no stick track repeating relays to make these signals stick signals; while the signal control relay 1HR is provided with a track repeating stick relay 5TPS to give the stick feature, but is lacking the track circuit control for an extended distance beyond the track section 5. These various features are optional with the 65 particular situations to be met in practice.

When a diverging route is set up, the directional stick relays associated with that route for the particular direction to be established are deenergized; but for other routes not established, 75

the directional stick relays for that direction remain energized. For example, it can be seen that when the track switch 9TS is reversed, it is unnecessary and in fact undesirable that the relay 7WS shall be deenergized upon the clearing of signal 2B. Thus, in order that the relay 7WS shall be maintained energized, an additional source of energy is provided from (+), through front contact 96 of switch repeating relay 9RP, wire 97, to wire 47 and thence through the circuits for relay 7WS, as above explained. However, the deenergization of the relay 9WS effects the deenergization of the succeeding directional stick relay (not shown) for that direction on the turn-out route. The reasons for this are evident, in that it is easily seen that the switch 5TS may be desired for use in other routes at the time that the switch 9TS is reversed, or it may be pre-positioned for a route also involving the switch 9TS, thereby saving time in setting up the entire route.

General summary.—The operation in general comprises the setting up of the route mechanically by operating the track switches of the interlocking plant to such positions as desired, followed by the movement of the proper signal control lever to a clear position depending upon the particular route which is desired to be established. The movement of a signal lever to a clear or proceed position, causes the directional stick relays for the route mechanically set up as governed by that signal, to be deenergized throughout the length of the route to the opposing governing signal. The deenergization of these directional stick relays causes the deenergization of the associated lock relays for that route, thereby preventing operation of the track switches. The deenergization of the lock relays in turn effects the completion of the electrical route selecting circuits, which allows the signal control relays to be selected in accordance with the route thus established, thereby causing the signal for that route to display a proceed indication.

In other words, an interlocking system has been described which provides route circuits corresponding to the actual track layout, which circuits cannot be completed until each of the track switches within the route being established has been locked, although such locking occurs subsequent to the movement of the corresponding signal control lever for that route.

Each signal is preferably provided with suitable approach locking means having associated therewith suitable time releasing means, as above described. Also, in accordance with the present invention, an additional feature is provided in that the approach locking is made ineffective in the event that trains are closely following each other on a caution signal.

Having thus shown and described an interlocking system as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention except as limited by the appended claims.

What we claim is:—

1. In an interlocking system for railroads, a

stretch of railway track, a plurality of track switches in said stretch of railway track, signals for governing traffic in opposite directions over said stretch of railroad track, and route means for said stretch of railroad track comprising, a 5 circuit including contacts assuming positions corresponding to the positions of said track switches, a route relay at each end of said circuit, means for applying to said circuit either of two polarities at each end, whereby the application of the 10 same polarity at both ends fails to energize said route relays, a lock contact associated with each of said track switches said lock contacts being included in said circuit for allowing said circuit to be completed only when the corresponding 15 track switches are locked, and means for clearing said signals dependent upon the energization of said route relays.

2. In an interlocking system for railroads, a stretch of railway track, a plurality of track 20 switches in said stretch of railway track, signals for governing traffic in opposite directions over said stretch of railroad track, a control lever for each of said signals operable to clear or stop 25 positions, means initiated by movement of any one of said control levers to a clear position for locking said track switches against operation, a route circuit having current flowing therein only when said track switches are locked and only when a signal lever is moved to a clear position, 30 and means for clearing the particular one of said signals corresponding to the particular control lever in a cleared position only if current is flowing in said route circuit.

3. In an interlocking system for railroads, a 35 stretch of track divided into a plurality of track sections, two signals one at each end of said stretch of track for governing traffic in opposite directions thereover, track switches associated with said track sections, means for operating 40 said track switches, control levers for each of said signals, two directional stick relays for each of said track sections, one of said stick relays being for one direction and the other of said stick relays being for the opposite direction, 45 means locking each of said track switches when either one of said directional stick relays for the corresponding track section is deenergized, and means clearing one of said signals only when the corresponding control lever is operated and the directional stick relays for the corresponding 50 direction are deenergized.

4. In an interlocking system for railroads, the combination with a track layout, of a plurality 55 of track switches to establish a large number of trackway routes, switch-position contacts associated with each of said track switches having circuit closing positions corresponding to the positions of their track points, switch machines for operating each of said track switches, means for manually governing said switch machines, 60 means for preventing said manual governing means from causing operation of said switch machines, lock contacts associated with each of said track switches having circuit closing positions assumed when their corresponding switch machines are locked against operation, wires connecting said switch-position contacts and said lock contacts to establish route circuits corresponding to the trackway routes established 65 by said track switches, a signal at each end of a trackway route, energizing means at each end of each route circuit for energizing the particular route circuit then established, interlocking means for preventing the energizing means at 70 75

one end of a route circuit from functioning when the energizing means at the other end of said route circuit is effective, and a signal control circuit governed jointly by said energizing means 5 and its associated interlocking means.

5. In an interlocking system for railroads, a track layout including a plurality of track switches to establish a large number of trackway routes, contacts associated with said track switches having circuit closing positions corresponding to the positions of their track points, wires connecting said contacts to establish route circuits corresponding to the trackway routes established by said track switches, a signal at 10 each end of each trackway route, energizing means at each end of each route circuit for energizing such route circuit when established, interlocking means for preventing the energizing means at one end of a route circuit from functioning when the energizing means at the other end of said route circuit is effective, a signal control circuit for each of said signals governed jointly by its corresponding energizing means and its associated interlocking means, and 15 means preventing the establishment of any route circuit until all of the track switches in the corresponding trackway route are locked against operation.

6. In an interlocking system for railroads, a track layout including a plurality of track switches to establish a large number of trackway routes, contacts associated with said track switches having circuit closing positions corresponding to the positions of their track points, wires connecting said contacts to establish route circuits corresponding to trackway routes established by said track switches, a signal at each end of each trackway route, manually governable energizing control means at each end of 20 each route circuit for energizing such route circuit when established, interlocking means for preventing the manually governable energizing control means at one end of a route circuit from functioning when the manually governable energizing control means at the other end of said route circuit is effective, signal control circuits for each of said signals governed jointly by its corresponding manually governable energizing control means and its associated interlocking means, means preventing the establishment of 25 any route circuit until all of the track switches in the corresponding trackway route are locked against operation, and means made effective by each of said manually governable energizing control means for effecting the locking of each track switch in said corresponding trackway route.

7. In an interlocking system; the combination with a track lay-out containing a plurality of routes each including a plurality of track switches and track sections; a lock relay for each track switch; a plurality of route circuits each corresponding to one of said routes and each including a wire for each track section, a double C5 throw circuit controller for each track switch assuming a position corresponding to the position of such track switch, and a back contact of the lock relay associated with each such track switch; and a signal at each end of each route controlled by the route circuit corresponding to such route.

8. In an interlocking system, the combination with a track layout including a plurality of track switches and track sections associated with such track switches to facilitate the establishment of

a plurality of routes, switch contacts for each track switch to manifest the position assumed by such switch, a lock relay for each track switch which if deenergized prevents power operation of such switch, a route circuit for each of said routes including switch contacts of the track switches included in said route and also including back contacts of the lock relay of each switch included in such route, and means for energizing such route circuit by current of a character depending on the direction in which traffic shall be permitted to move over said route. 5

9. In an interlocking system, the combination with a track layout including a plurality of track switches and track sections associated with such track switches to facilitate the establishment of a plurality of routes, switch contacts for each track switch to manifest the position assumed by such switch, a lock relay for each track switch which if deenergized prevents power operation 10 of such switch, a route circuit for each of said routes including switch contacts of the track switches included in said route and also including back contacts of the lock relay of each switch included in such route, means for energizing such route circuit by current of a character depending on the direction in which traffic shall be permitted to move over said route, and means 15 manually controllable for deenergizing the lock relays associated with the track switches of a set up route.

10. In an interlocking system, the combination with a track layout including a plurality of track switches and track sections associated with such track switches to facilitate the establishment of 20 a plurality of routes, switch contacts for each track switch to manifest the position assumed by such switch, a lock relay for each track switch which if deenergized prevents power operation of such switch, a route circuit for each of said routes including switch contacts of the track switches included in said route and also including back contacts of the lock relay of each switch included in such route, means for energizing such route circuit by current of a character depending on the direction in which traffic shall be permitted to move over said route. 25 set up route.

11. In an interlocking system, the combination with a track layout including a plurality of track

switches and track sections associated with such track switches to facilitate the establishment of a plurality of routes, switch contacts for each track switch to manifest the position assumed by such switch, a lock relay for each track switch which if deenergized prevents power operation of such switch, a route circuit for each of said routes including switch contacts of the track switches included in said route and also including back contacts of the lock relay of each switch included in such route, means controlled by the points of the track switches in a set up route for selecting the lock relays of such track switches, and manually operable means for deenergizing said selected lock relays, whereby a route circuit may be closed manually as soon as the route it represents has been set up. 30

12. In an interlocking system, the combination with a track layout including a plurality of track

switches and track sections associated with such track switches to facilitate the establishment of a plurality of routes, switch contacts for each track switch to manifest the position assumed by such switch, a lock relay for each track switch which if deenergized prevents power operation of such switch, a route circuit for each of said routes including switch contacts of the track switches included in said route and also including back contacts of the lock relay of each switch included in such route, means controlled by the points of the track switches in a set up route for selecting the lock relays of such track switches, and manually operable means for deenergizing said selected lock relays, whereby a route circuit may be closed manually as soon as the route it represents has been set up.

13. In an interlocking system, the combination with a track layout including a plurality of track switches and track sections associated with such track switches to facilitate the establishment of a plurality of routes, switch contacts for each track switch to manifest the position assumed by such switch, a lock relay for each track switch which if deenergized prevents power operation of such switch, a route circuit for each of said routes including switch contacts of the track switches included in said route and also including back contacts of the lock relay of each switch included in such route, means controlled by the points of the track switches in a set up route for selecting the lock relays of such track switches, manually operable means for deenergizing said selected lock relays, whereby a route circuit may be closed manually as soon as the route it represents has been set up, and a signal controlled by such route circuit.

14. In combination, a stretch of track, a traffic device included within said stretch of track and operated for at times breaking the continuity of said stretch of track, signals at opposite ends of said stretch for governing traffic in both directions over said stretch of track, a circuit extending between two traffic governing relays respectively associated with the opposite ends of said stretch of track, a current source at each end of said circuit for supplying current to said circuit but normally disconnected therefrom, a manually controlled relay associated with each end of said circuit, a contact included in said circuit which contact is closed only when the continuity of said stretch is completed by said traffic device, a second contact included in said circuit which second contact is closed only when said traffic device is locked to prevent its operation, means governed by each said manually controlled relay when energized to connect the associated current source with said circuit, means for clearing the one of said signals at the end of said stretch having both its associated said traffic governing relay and said manually controlled relay energized so as to permit traffic to move through said stretch of track in a direction determined by the end at which said circuit is supplied with current, and means effective upon the energization of any one of said manually controlled relays for closing said second contact.

15. In combination, a stretch of railway track, a power operated track switch included in said

stretch, a traffic governing circuit connecting two traffic governing relays respectively associated with opposite ends of said stretch and which circuit is normally short circuited, a switch position reflecting contact included in said traffic governing circuit and closed only when said stretch of track is continuous, a lock contact included in said traffic governing circuit and closed only when said power operated track switch is locked to prevent its operation, a source of current associated with each end of said traffic governing circuit for applying current to said circuit but both normally disconnected therefrom, a signal normally indicating stop located at each end of the stretch to govern traffic through said stretch in opposite directions, a control circuit for each signal having two normally open contacts, a first circuit controller governed from a central dispatching office for closing one of said contacts for the control circuit of a signal, a second circuit controller governed from the central dispatching office for removing the short circuit of the traffic governing circuit and for connecting therewith the current source associated with the direction of traffic governed by said signal and for energizing the traffic governing relay associated with that direction of traffic, means governed from the central dispatching office for closing said lock contact, and means controlled by said traffic governing relay when energized to close the other contact of the control circuit for said signal, whereby only the signal for a particular direction can be cleared at the same time, and whereby any particular signal cannot be cleared unless said power operated track switch is locked.

16. In an interlocking system for railroads; a stretch of railway track; a plurality of track switches in said stretch of track; a power operated switch machine for operating each of said track switches; switch control circuits for controlling said switch machines; signals for governing traffic over said stretch of track and said track switches in either direction; signal control circuits for controlling said signals; manually governed means for controlling said switch and signal control circuits; an electro-responsive locking means having front and back contacts of which the front contacts are rendered effective upon deenergization thereof and opening of such front contacts to prevent operation of their switch machines, said locking means being deenergized in response to actuation of said manually governed means to a condition to cause a signal to tend to indicate proceed; and means including back contacts of said locking means for electrically interlocking said track switches and signals so that said signals can be caused by said manually governed means through their respective control circuits to display proceed indications only when said locking means is rendered effective and said back contacts are closed, so that all of said switch machines are prevented from operating through their respective control circuits, and so that signals for governing traffic in one direction only can be caused to display proceed indications.
